B. E. GOVE.

EXTENSION COMPASSES.

(Application filed July 28, 1902.)

(No Model.)

UNITED STATES PATENT OFFICE.

BURT E. GOVE, OF WINTHROP, MASSACHUSETTS.

EXTENSION-COMPASSES.

SPECIFICATION forming part of Letters Patent No. 714,575, dated November 25, 1902.

Application filed July 23, 1902. Serial No. 116,733. (No model.)

To all whom it may concern:

Be it known that I, BURT E. GOVE, a citizen of the United States, residing at Winthrop, in the county of Suffolk and State of Massachusetts, have invented new and useful Improvements in Extension-Compasses, of which the following is a specification.

This invention relates to extension-compasses and contemplates the provision, in connection with a pair of compasses having legs of equal length, of means for holding the said legs in immovable adjusted position and a particular form of socket in connection with one leg, whereby extension devices may be adjustably connected thereto and of themselves adjustable and adapted to hold a pencil or other marking device at different distances from one of the legs of the compasses and which serves as a centering means of support.

The invention also contemplates the details of construction and arrangement of the several parts, which will be more fully hereinafter described and claimed.

25 The object of the invention is to provide a simple and effective device of a comparatively inexpensive nature and convenient in use.

In the drawings, Figure 1 is a perspective view of the extension-compasses embodying the features of the invention and shown arranged for use. Fig. 2 is a rear elevation of the compasses proper without the extension attachments. Fig. 3 is an edge elevation of the upper portion of the compasses proper. Fig. 35 4 is a detail perspective view of a segmental head-plate forming a part of the compasses proper. Fig. 5 is a detail perspective view of a connecting-sleeve for the extension devices.

40 Similar numerals of reference are employed to indicate corresponding parts in the several views.

The numerals 1 and 2, respectively, designate the legs of the compasses proper, having lower pointed terminals 3 and the usual form of joint 4 at their upper ends. The leg 2 in the outer edge portion thereof, near the upper end, is formed with a screw-socket 4, as shown by dotted lines in Fig. 2, and the front 50 side of the upper part of the leg 1 is also provided with a screw-socket 5. The leg 1 also has an outwardly-projecting tubular socket

6, which is preferably integrally formed therewith and has a clamping-screw 7 extending thereto, and when the compasses are used without the parts which will be hereinafter explained they may serve in the usual capacity of dividers, or a pencil may be inserted in the socket 6 for convenience in laying out circles or indicating arcuate measurements. 60 The socket 6, however, has a particular use which will be hereinafter set forth.

A segmental holding-plate 8 is applied to the head of the compasses and is held in place by a pin 9, having a reduced extremity 10, 65 which is fitted in the center of the joint 4, and in the lower edge of the said plate a segmental slot 11 is formed and of which the pin 9 is the center. A clamping-screw 12 projects through the slot 11 and engages the socket 5 70 in the leg 1 to adjust the said leg and firmly secure it at different distances from the leg 2. The one side edge of the plate 8 near its lower edge has a rearwardly-extending right-angular ear 13, with an aperture or opening 14 75 therein, through which is passed a clamping-screw 15. Secured to the upper portion of the side edges of the leg 2 adjacent to the location of the ear 13 is a flat spring 16, which has its lower end projected or bowed outwardly to bear against the inner side of the said ear, and through the lower end of this spring the clamping-screw 15 also passes and engages the socket 4, which is deep enough to permit the screw 15 to have considerable 80 adjusting movement. The function of the spring 16 is to establish a tight connection between the plate 8 and the leg 2 through the medium of the clamping-screw 15, so that the said leg may be practically held rigid in relation to the plate to serve as a centering means, and, furthermore, said spring acts to hold the plate in proper position relatively to the upper connected ends of the legs of the compasses. This plate 8 may be used in connection 95 with the compasses independently of the extension devices, which will be hereinafter explained, to hold the leg 1 positively adjusted in relation to the leg 2 and overcome any disadvantages that may arise by looseness of the joint due to wear. The plate 8 is particularly intended, however, to hold the leg 1 in rigid adjustment when the extension devices are used in connection therewith.

The extension devices comprise a rod 17, which is adjustably inserted at one end in the socket 6 and firmly held against movement by the clamping-screw 7. Coöoperating with 5 the rod 7 is a pencil-carrying rod 18, having a sleeve 19 on the outer end thereof, which is disposed at an oblique angle and provided with a clamping-screw 20. The inner ends of the rods 17 and 18 are overlapped and inserted through an elliptical connecting-sleeve 21, also provided with a clamping-screw 22. In arranging the compasses and extension attachments for use the leg 1, as shown by Fig. 1, is in a plane at right angles to the leg 15 2, and the rod 17 is inserted in the socket 6 and adjusted to regulate its longitudinal projection beyond the terminal of the leg 1, as may be desired. The outer end of the rod 17 and the inner end of the rod 18 are then passed 20 through the sleeve 21 and overlapped to such extent as may be found desirable and secured against movement by tightening the clamping-screw 22. A pencil 23 is inserted 25 in the sleeve 19 on the outer end of rod 18 and pushed down until the point thereof engages the surface on which the compasses and extension attachment are adapted to be used and then firmly secured through the medium of the clamping-screw 20. The sleeve 30 19 is disposed at an outward oblique angle in relation to the rod 18 to better arrange the pencil for defining a circle or arc and to project the marking extremity of the pencil or other marking device at the lower end there- 35 of with obvious advantages. The pencil or other device held by the sleeve 19 may be readily projected outwardly from or drawn nearer to the leg 2 by loosening the sleeve 21 and correspondingly moving the overlapped 40 ends of the rods 17 and 18 or by shifting the rod 17 in the socket 15.

The improved device will be found exceptionally useful, and a long or short pencil can be disposed in the socket and economy thus 45 results in the use of the marking means employed in connection with the improved device. The segmental plate 8 or quadrant being applied to the sides of the legs 1 and 2 instead of passing through the latter, as in ordinary forms of compasses, and being of the shape shown strengthens the compasses and can be applied in operative position or detached and carried in the pocket with much

less annoyance, and the clamping-screws are in a much more protected position and much 55 less liable to become loosened. Furthermore, the plurality of adjustments resident in the compasses proper and the extension devices provide for the formation of circles of any size and avoid the procurement and use of a 60 large and small instrument.

Changes in the proportions, dimensions, and minor details of construction may be resorted to without departing from the principle of the invention.

Having thus described the invention, what is claimed as new is—

1. The combination with compasses, of a quadrant-plate having a pin forming the fulcrum means for the legs of the said compasses 70 and also provided with a segmental slot, means for securing the plate to one of the legs of the compasses, and clamping means engaging the said slot and the other leg of the compasses whereby the latter may be adjusted 75 and held in fixed relation to the first-mentioned leg.

2. The combination with a pair of compasses, of a spring depending from the upper portion of the outer side edge thereof, a quadrant-plate applied to the outer sides of the upper portions of the legs and having a segmental slot therein and an angular projection near the lower edge at one side, a clamping-screw passing through said slot into one 85 of the legs, and a clamping-screw extending through the projection and the spring into the other leg.

3. The combination of a pair of compasses having means for holding the legs thereof in 90 rigid spaced relation, one of the legs being provided with a socket and a clamping-screw, an extension-rod adjustably mounted in the said socket, a second rod having a socket at its outer end adapted to receive a pencil, and 95 an elliptical sleeve to which the outer end of the first-mentioned rod and the inner end of the rod carrying the socket are passed and adjustably held.

In testimony whereof I affix my signature 100 in presence of two witnesses.

BURT E. GOVE.
